Inventor:
George Qualman,
By Almon Hall, Atty.

UNITED STATES PATENT OFFICE.

GEORGE QUALMAN, OF TOLEDO, OHIO.

VACUUM-CLEANER ATTACHMENT.

1,376,971.

Specification of Letters Patent.

Patented May 3, 1921.

Application filed March 11, 1920. Serial No. 365,101.

To all whom it may concern:

Be it known that I, GEORGE QUALMAN, a citizen of the United States, residing at Toledo, in the county of Lucas and State of Ohio, have invented certain new and useful Improvements in Vacuum-Cleaner Attachments; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to an attachment for electric vacuum cleaners, whereby, by means of a cheap, simple and highly efficient device, these cleaners, as ordinarily constructed, may be utilized to take the place of the driers commonly employed by women for drying their wet hair after a shampoo.

In carrying out my invention, I avail myself of the presence of a vacuum-fan in an electric vacuum cleaner, which at its discharge side is a blower, and of the presence of electric conductors capable of furnishing an electric current for heating the requisite air-currents.

To these ends, my invention consists of the devices, construction and arrangement of parts hereinafter described, and illustrated in the accompanying drawings in which—

Figure 1, is a side-elevation of my device; Fig. 2, a top-plan view of the same in central horizontal section, taken on line α — α Fig. 1; Fig. 3, an enlarged like view of a portion of the same, and Figs. 4 and 5, side-views of the supporting diaphragms herein-after referred to, detached.

Corresponding numerals represent like parts throughout the drawings.

In the drawings, 1 is the discharge-pipe of the fan-chamber of an electric vacuum cleaner, of the usual or any preferred sort, the elements of which are so well understood as to require no further illustration or description here. 2 is an elbow section of pipe which, at one end, forms a slip-joint 3 with the pipe 1, and at its other end engages, as a slip-joint 4, the smaller end of the tubular flaring funnel-shaped member 5.

Diametrically disposed in the chamber of the funnel-shaped piece 5 are two diaphragms 6 and 7 having therethrough numerous openings 8, of sufficient extent to permit the free passage of air-currents. Each

of the diaphragms has a central opening 9 in which openings are supported the opposite ends of a tube or bar 10, of a suitable refractory insulating material, preferably, as in the present instance, a porcelain tube. Around this tube are spirally wound heating strips or coils 11, of wire of high electrical resistance. One end of the heating coil 11 is connected with inleading wire 12, the other end being connected with the out-leading wire 13. These wires are connected with binding-posts 14 and 15, mounted on the part 5, which posts are adapted also for connection with wires 16 and 17, connected with a suitable source of current, as, for instance, the inleading and outleading wires of the motor of the vacuum cleaner.

The operation of my device is as follows: The vacuum cleaner,—or that portion of it which contains the fan,—is placed on a table, and the usual dust-tube is replaced by the elbow 2 forming the joint 3, the interior of the part 5 being now in communication with the blower side of the fan-chamber. The wires 16—17 being placed in circuit and the motor of the cleaner being in motion, the heating element 11 soon becomes hot, and the blast of air issuing from the mouth of the funnel is heated as determined by the extent and efficiency of the heating element and the potential of the current supplied. The operator, seated by the table, may direct the blast from the part 5 in any direction, vertically, by means of the slip-joint 3.

Having described my invention, what I claim and desire to secure by Letters Patent of the United States is,—

1. In a device of the described character, a tubular member, foraminous diaphragms in the chamber of said member, a heating element carried by and between said diaphragms, means for connecting said heating element with a suitable source of electricity, and means for detachably connecting the inlet end of said tubular member with the outlet member of a vacuum cleaner.

2. In a device of the described character, a funnel-shaped member, two foraminous diaphragms in the chamber of said member, a tube of non-conducting refractory material having its ends supported in said diaphragms, an electric heating element coiled about said tube, an inleading wire and an out-leading wire operatively connected with the terminals of the heating element, and means for detachably connecting the inlet

end of the funnel-shaped member with the blower side of an electric vacuum cleaner.

3. Means for utilizing an electrically driven vacuum cleaner as a hair drier, comprising a tubular member adapted to direct an air-current, an electric heating element in said tubular member and traversed by such air-current, means for connecting the inlet end of said tubular member with the 10 discharge opening of a vacuum cleaner, and a conductor for the heating element operatively associated with the conductor for such vacuum cleaner.

4. A hair drying attachment for an electric vacuum cleaner comprising a tubular member adapted to discharge and direct an air-current, means for connecting the inlet end of said tubular member with the discharge opening of a vacuum cleaner, an electric heating element in said tubular member,

and electrical conductors common to said heating member and such vacuum cleaner.

5. In a device of the described character, a funnel-shaped tubular member, two foraminous diaphragms in the chamber of said member, an electric heating element carried by and between said diaphragms, conductors for placing the heating element in an electric circuit, an elbow-pipe connected at one end with the smaller end of the funnel-shaped member, the other end of the elbow-pipe being adapted for connection as a rotatable slip-joint with the discharge-pipe of an electric vacuum cleaner.

In testimony whereof I affix my signature 35 in presence of two witnesses.

GEORGE QUALMAN.
